WARP THREAD GUIDING MEANS FOR TEXTILE WARPING MACHINES

Allan William Henry Porter, Burton-on-Trent, England, assignor to F.N.E. Machinery Manufacturing Co. Ltd., Burton-on-Trent, England, a British company

Application July 5, 1957, Serial No. 670,077

Claims priority, application Great Britain July 13, 1956

6 Claims. (Cl. 28—38)

This invention relates to warping machines for winding warp threads on to warp beams for use in warp knitting machines and looms. A representative machine of this general type is shown in U.S. Patent No. 2,738,565 to Robertson and Porter.

In such machines the beam, which is usually in the form of a cylinder with a flange at each end, is supported between two end stocks and is rotated so that the warp threads, which are initially fixed side by side along the length of the beam, are drawn from a creel. The machine commonly has one or more tension rollers which are arranged parallel to the warp beam and around which the threads are led on their passage from the creel to the warp beam, and one or more reeds through which the threads pass during this passage.

It is important that the spacing of the individual warp threads along the beam is accurately maintained and it is for this purpose that the threads are passed through the reed which is mounted as near as is practicable to the warp beam. The reed cannot, however, be mounted close to the surface of the warp threads wound on to the beam because, especially when the warp beam is empty, the end flanges of the warp beam extend radially outwards for a considerable distance.

In practice, therefore, the last reed through which the warp threads pass on their passage to the warp beam is situated a considerable distance from the warp beam and, particularly when very fine threads are being wound on to a warp beam, a slight axial displacement of the individual threads is likely to occur between the last reed through which the warp threads pass and the point at which the threads pass on to the warp beam. The threads are very closely spaced side by side and when such an axial displacement occurs two or more threads may become trapped together as they are wound on to the beam. Such trapping of the threads causes difficulties when the warp beam is in use on a warp knitting machine or a loom and results in unevenness of the fabric produced. The difficulties caused by trapping are accentuated with high twist threads, because the threads are liable to roll together due to the twist and intermingle in a random manner. Also, when the unthrown or low twist threads are used in which the filaments which make up each individual thread lie substantially parallel to one another, if adjacent threads are trapped, and so laid together, the filaments intermingle so that it is impossible to distinguish which is their parent thread.

To reduce or avoid this axial displacement of the warp threads, a warping machine according to the present invention has a roller mounted on a movable axis and a reed, which is movable with the axis of the roller, mounted adjacent the roller, the machine being capable of being threaded up in such a way that the warp threads pass through the reed and around the roller on their passage to the warp beam and then pass immediately from the surface of the roller on to the warp beam, the roller being in contact with the surface of the mass of warp threads wound on to the warp beam, so that the warp

2

threads are directly sandwiched between the roller and the warp beam as they pass on to the warp beam.

Preferably both the roller and the reed are mounted on a pivoted arm or a pair of pivoted arms so that they swing away from the warp beam as the diameter of the mass of warp threads upon the beam increases. When the roller is mounted in this way, it may be arranged so that a component of its own weight urges it towards the warp beam, but this component may be partly counteracted or completely balanced by the resultant of the tension of the warp threads passing on to and off the roller.

An adjustable counterbalance weight may also be provided on the pivoted arm or arms on the side of the pivot away from the tension roller so that the force urging the roller towards the beam can be altered independently of the tension in the warp threads.

The reed moves away from the warp beam together with the roller as the mass of warp yarns on the warp beam builds up, and thus the spacing between the reed and the roller is kept constant. Because there is no relative movement, the distance between the reed and the tangent point at which the threads pass onto the roller may be kept short.

25 The axial spacing of the warp threads is therefore accurately gauged at the point where the warp threads pass on to the roller. The axial spacing of the warp threads in the direction along the length of the warp beam is maintained by the friction between the threads and the 30 roller and similarly by the friction between the threads being wound on to the beam and those already on the beam. Thus, since the threads pass immediately from the roller on to the beam, the possibility of trapping of the warp threads due to transverse displacement is very 35 greatly reduced or substantially eliminated.

The roller may be provided with a brake so that it can exert a drag on the warp threads passing over it and so act as a tension roller. The arrangement of the tension roller 40 immediately adjacent the warp beam in this way is particularly advantageous since there is no possibility of creep occurring in the threads between their final tension being applied to them and their being wound in position on the warp beam, so that an even tension is maintained.

An example of a warping machine constructed in accordance with the invention is illustrated in the accompanying drawings in which:

Figure 1 is a side elevation of the machine showing the warp beam partly in section;

Figure 2 is a section through the warp beam and tension roller on the line II—II of Figure 1, to a larger scale; 50 and

Figure 3 is a sectional detail to an enlarged scale of part of one end of the tension roller, showing an end flange.

55 As shown in Figure 1 the warping machine has a frame 1 with two legs 2 on which it is supported from a foundation and also two arms 3 and 4 projecting upwards from the frame 1. The machine has a second frame 1 with legs 2 and arms 3 and 4 on its opposite side. A warp beam 5 is supported in bearings 6 carried in the arms 3. 60 The warp beam is rotated in the direction shown by the arrow 7 by an electric motor, enclosed within a casing 8. The motor is controlled by control gear operated by a handle 9.

65 Warp threads 10, to be wound on the warp beam, are led from a creel, which is not shown, through a reed 11 carried on an arm 12 fixed to the arm 4, around a tension roller 13 carried on an arm 14, around a second tension roller 15 and then through a conventional stop motion 16. The tension rollers 13 and 15 are provided with a brake band 17 on which a weight 18 is hung. By increasing the weight 18, the braking force exerted by

the band 17 on the tension rollers 13 and 15 can be increased, to increase the tension imparted by the rollers to the warp threads 10.

After leaving the stop motion at 16, the sheet of warp threads 10 passes across the top of the machine through a reed 19 and around a tension roller 20. From the tension roller 20 the threads pass directly on to the surface of the core 21 of the warp beam 5.

The tension roller 20 is pivotally mounted in a bearing 23 in an L-shaped arm 24 and in a similar bearing in a second L-shaped arm on the other side of the machine. The L-shaped arm 24 is pivoted to the frame 1 by a pin 25. The tension roller 20 is thus able to swing about the pivot 25 from the position shown in full lines in Figure 1 to the position shown at 20¹ in chain dotted lines in Figure 1.

The reed 19 is carried on the L-shaped arms 24 and therefore swings with the tension roller 20.

As shown in Figure 2, the tension roller 20 has a small bevelled flange 26 at each end. The flanges 26 have inwardly directed sloping faces which as indicated at 27 confine the outermost threads 10 as they are wound on to the warp beam 5 and prevent them spilling outwards and being trapped in the clearance spaces which are necessary between the ends of the tension roller 20 and the flanges 29 of the warp beam. In this example each flange 26 projects radially for a length of .030 inch and has a maximum axial thickness of .020 inch. A detail of the flanges 26 is shown in Figure 3.

The weight of the tension roller 20 and the L-shaped arms 24 produces a counterclockwise moment about the pivot 25 as seen in Figure 1 and thus tends to swing the tension roller 20 to the left into contact with the mass of warp threads 10 wound on to the warp beam 5. This moment is partly counteracted by the resultant of the tensions T and T¹ of the warp threads 10 passing on to and off the tension roller 20. As the diameter of the mass of warp threads 10 on the warp beam 5 increases, the tension roller 20 and the parts connected to it are swung to the right as shown in Figure 1 about the pivot 25. As this occurs the path of the warp threads 10 moves towards the position shown at 10¹. The L-shaped arms 24 are cranked inwardly at 28 (Figure 2) to enable them to fit within the end flanges 29 of the warp beam 5. The tension roller 20 has an internal brake shoe 30.

I claim:

1. In a warping machine of the type comprising a frame, a warp beam rotatably mounted on said frame and means for rotatably driving said warp beam, the improvement comprising a roller rotatably mounted in a position adjacent said beam with the surface of said roller in contact with the surface of said beam, a member mounted on said frame and carrying said rotatable roller, said member being movable on said frame to allow said roller to move towards and away from the surface of said beam, and a reed mounted on said movable member adjacent a part of the surface of said roller remote from said beam, said roller being interposed in the path to be travelled by warp threads approaching said beam, whereby said threads pass through said reed, frictionally engage an arcuate portion of the surface of said roller and then pass directly from the surface of said roller on to said beam, said warp threads being directly sandwiched between said roller and said beam as they pass on to said beam.

2. In a warping machine of the type comprising a frame, a warp beam rotatably mounted on said frame and means for rotatably driving said warp beam, the improvement comprising an arm pivotally mounted on said frame for movement towards and away from said beam, a roller rotatably mounted on said arm in a position adjacent said beam with the surface of said roller in contact with the surface of said beam, said arm and said roller being swingable away from said beam as the number of turns of warp threads wound on said beam increases, and a

reed mounted on said arm adjacent a part of the surface of said roller remote from said beam, said roller being interposed in the path to be travelled by warp threads approaching said beam, whereby said threads pass through said reed, frictionally engage an arcuate portion of the surface of said roller and then pass directly from the surface of said roller on to said beam, said warp threads being directly sandwiched between said roller and said beam as they pass on to said beam.

3. In a warping machine of the type comprising a frame, a warp beam rotatably mounted on said frame and means for rotatably driving said warp beam, the improvement comprising a roller rotatably mounted in a position adjacent said beam with the surface of said roller in contact with the surface of said beam, a member mounted on said frame and carrying said rotatable roller, said member being movable on said frame to allow said roller to move towards and away from the surface of said beam, a brake for retarding the rotation of said roller, and a reed mounted on said movable member adjacent a part of the surface of said roller remote from said beam, said roller being interposed in the path to be travelled by warp threads approaching said beam, whereby said threads pass through said reed, frictionally engage an arcuate portion of the surface of said roller and then pass directly from the surface of said roller on to said beam, said warp threads being tensioned as they pass around said retarded roller and being directly sandwiched between said roller and said beam as they pass on to said beam.

4. In a warping machine of the type comprising a frame, a warp beam rotatably mounted on said frame and means for rotatably driving said warp beam, the improvement comprising an arm pivotally mounted on said frame for movement towards and away from said beam, a roller rotatably mounted on said arm in a position adjacent said beam with the surface of said roller in contact with the surface of said beam, a brake for retarding the rotation of said roller, said arm and said roller being swingable away from said beam as the number of turns of warp threads wound on said beam increases, and a reed mounted on said arm adjacent a part of the surface of said roller remote from said beam, said roller being interposed in the path to be travelled by warp threads approaching said beam, whereby said threads pass through said reed, frictionally engage an arcuate portion of the surface of said roller and then pass directly from the surface of said roller on to said beam, said warp threads being tensioned as they pass around said retarded roller and being directly sandwiched between said roller and said beam as they pass on to said beam.

5. In a warping machine of the type comprising a frame, a warp beam rotatably mounted on said frame and means for rotatably driving said warp beam, the improvement comprising an arm pivotally mounted on said frame for movement towards and away from said beam, a roller rotatably mounted on said arm in a position adjacent said beam, said roller being urged by its own weight and the weight of said arm into contact with the surface of said beam, the said arm and said roller being swingable away from said beam as the number of turns of warp threads wound on said beam increases, and a reed mounted on said arm adjacent a part of the surface of said roller remote from said beam, said roller being interposed in the path to be travelled by warp threads approaching said beam whereby said threads pass through said reed, frictionally engage an arcuate portion of the surface of said roller and then pass directly from the surface of said roller on to said beam, said warp threads being directly sandwiched between said roller and said beam as they pass on to said beam.

6. A warping machine as claimed in claim 1, further comprising a small flange of bevelled cross-section projecting radially around each end of said roller, the inner

face of each of said flanges sloping outwards towards
the ends of said roller.
